UNITED STATES PATENT OFFICE.

MICHAEL E. NEENAN AND JOHN J. NEENAN, OF NEW YORK, N. Y., ASSIGNEES TO
NEENAN ELEVATOR CORPORATION, A CORPORATION OF NEW YORK.

ELECTROMAGNETICALLY-CONTROLLED BRAKE.

Application filed July 23, 1918, Serial No. 246,409. Renewed July 8, 1921. Serial No. 483,343.

To all whom it may concern:

Be it known that we, MICHAEL E. NEENAN and JOHN J. NEENAN, citizens of the United States, and residents of New York city, in the county of Bronx and State of New York, have invented certain new and useful Improvements in Electromagnetically- Controlled Brakes, of which the following is a specification.

10 This invention relates to improvements in the arrangement and construction of electromagnetically controlled brakes particularly adapted for the control of elevator or like apparatus. The device of our present invention is designed particularly to produce a device which will be positive and dependable in its action, durable, of well balanced construction and of an improved construction possessing a greatly increased area of effective braking surface whereby high efficiency in its operation is secured.

15 The described and other valuable features of our invention are illustrated in the accompanying drawings wherein like reference characters are applied to the corresponding parts in the several views.

20 Referring to the drawing, Fig. 1 is a view in side elevation illustrating a preferred embodiment of the features of our invention. Fig. 2 is a similar view from the opposite side thereof. Figs. 3 and 4 are views in side elevation showing desirable modified forms of the device. Fig. 5 is an end elevation of the embodiment shown in Fig. 1. Fig. 6 is a similar view of the construction shown in Fig. 2. Fig. 7 is a longitudinal sectional view of a desirable magnet construction. Fig. 8 is a similar view showing a modified form thereof and Fig. 9 is a plan view of the 25 brake shoe supporting members of Fig. 1.

Referring to the drawings wherein we have shown desirable embodiments of our invention, 1 indicates a brake drum or cylinder mounted upon the usual brake shaft 2 which 30 in the manner well understood is connected to the elevator, derrick, winch, or other apparatus to be controlled.

35 In accordance with our invention we provide oppositely arranged and pivotally supported brake members or brake shoes 3 and 4 to have frictional braking engagement with the peripheral surface of the brake drum 1. As shown, the brake members 3 and 4 are pivotally supported up a bearing

pin 6 fitted to a supporting standard or 55 base 7. The respective brake members 3 and 4 are each formed with their opposed or inner surfaces substantially conforming in contour to the peripheral surface of the drum 1, and upon their inner surfaces they are 60 each provided with suitable friction metal or other material best suited to produce the desired braking effect. Means are provided normally to exert pressure upon the brake members to force them into braking contact 65 with the drum. A simple and effective means is here shown for this purpose, consisting of a pressure bolt 8 fitting apertures in the upper end portions of each of the 70 brake members above the drum and having its ends extending at each side outwardly from the brake members. The outwardly extended ends of the bolt are threaded as shown to receive the bearing nuts 9 and lock nuts 10 and interposed between the bearing 75 nuts and suitable bearing shoulders 11 formed on the brake members the compression springs 12 are arranged and held by suitable washers 13. As readily understood the pressure of the springs 12 is regulated by adjusting the nuts 9 and the 80 pressure thus determined normally will be effective to press the brake members into engagement with the brake drum 1. The arrangement as described is simple and substantial and employs braking surfaces acting upon both sides of the brake drum and upon substantially the entire peripheral surface of the drum so as to obtain a very effective 85 braking effort. Moreover this arrangement as illustrated, requires but the single resilient or pressure element, or means, to actuate both of the brake-members and further attendant upon this arrangement the 90 adjusting of the bearing nuts 9—9 determines the pressure to be exerted upon both of the brake members whereby the braking pressures are perfectly balanced, resulting in 95 equal wear upon the surfaces.

To release the brake when it is desired so 100 as to permit the rotation of the drum, electro-magnetically operated means are employed, as here shown, consisting of a magnet M having a movable armature suitably connected to the brake members whereby 105 when the magnet is energized the brake-members will be moved outwardly against the pressure of the springs 12 and away

from frictional engagement with the drum. This may be effected with magnets of various designs and arrangements.

In Figs. 1 and 2 we have shown a desirable construction wherein the brake-members are each formed with outwardly extending arm portions 14—14 which are formed and arranged in crossed-over relation to overlie the drum and are provided with rearwardly directed opposed shoulders 15—15. The magnet M is positioned between these shoulders, being supported by a suitable bracket 16. This magnet may be of conventional double-solenoid type comprising a suitable coil 17 having movable armatures 18—18 which are drawn inwardly under the influence of the field of the coil when the latter is energized. As shown the outer end of the armatures are passed through the shoulders 15 and have the nuts 19—19 threaded on their outer ends to engage the shoulders. In the manner readily understood when the magnet is energized, its cores or armatures are moved inwardly and the engagement of the nuts 19 with the shoulders 15 imparts the movement to the brake members whereby they are moved outwardly away from the braking engagement with the drum and against the influence of the springs. By the described simple arrangement we have provided for the separation of the brake members by a magnet employing inwardly drawn armatures.

In Figs. 3, 4, 7 and 8 we have shown arrangements wherein in accordance with my invention special forms of magnets are employed which are arranged to release the brake members by a separating or outward movement. In the construction there shown the brake-members are each provided with an upwardly extending arm or shoulder 14 on its own side of the drum and the magnet M employed is designed to impart an outwardly directed separating movement thereto.

In the construction of Figs. 3 and 7 the coil 17 is wound upon the core tube 21 to which are secured the usual retaining collars 22—22 for the coil. These parts are, as shown, supported in stationary position by a suitable bracket. The magnet is provided with the oppositely arranged movable armatures or solenoid cores 23—24 slidably fitted within the tube 21 within the field of the magnet coil 17. As shown in Fig. 7 each of the armatures 23—24 is formed with longitudinally extending apertures therein through which connecting rods 25—26 from the other of the armatures extends so that from each side of the magnet connection is made to the armature core of the opposite side. By this arrangement when the armatures are moved or drawn within the coil the other ends of the connections 25 and 26 are separated. The armature 23 is here

shown provided with a single central bore or aperture 28 through which the connection 25 to the armature 24 is extended and the latter armature 24 is provided with two bores 29 there-through to receive the connections 26—26 as shown, the latter being connected to the armatures 23. The connections 25 and 26 are suitably connected to each of the brake members to operate the same to release the braking engagement. In the construction shown in Fig. 3 the connections are each provided with extensions 30 passed through apertures in the shoulders 14 of the brake members 3 and 4 and provided on their outer ends with retaining nuts 31 and also provided with inner shoulders 33 to engage the shoulders 14 to impart the outward thrust thereto.

Means are shown adapted to limit the separating movement of the brake members consisting of a threaded rod 34 extending through both of the shoulders 14 and having stop nuts 36—36 on its outwardly extended ends.

In Figs. 4 and 8 we have shown further desirable modification wherein the magnet coil is not stationary supported but is connected to and carried by one of the brake members while the armature is connected to the other of the brake members. As shown, the coil support 40 has laterally extending perforated ears 41—42. A pivoted pin 43 is fitted to one of the ears and to the shoulder 14 of the brake member 4 whereas the perforation of the ear 41 is in the form of a slot 44 in which a pin 45 carried by the brake-member 3 is fitted whereby the magnet coil is supported and movably connected to one of the brake members 4 as shown. The armature 47 of the magnet as best shown in Fig. 8 is provided with a connection 49 which is connected at its other end to the brake member 3. In this arrangement the slot 44 and pin fitted thereto may act to limit the separating movement of the parts.

While we have described and illustrated desirable embodiments of our invention it will be understood that many other modifications thereof can be made without departing from our invention, and it is therefore intended that all matter herein shall be interpreted as illustrative and not in a limiting sense.

Having described our invention, we claim:

1. A device of the character described comprising a rotatable brake drum and oppositely arranged movable brake-shoe members adapted for frictional braking engagement with the drum, said brake-shoes having arm portions at their upper ends extending inwardly over the drum and in crossed-over relation, resilient pressure means operative to move the brake-shoe members into braking engagement and electro-magnetic means connected to the arm portions of the respec-

tive shoes and adapted to release the brake-shoes by inwardly moving the arm portions, substantially as described.

2. A device of the character described comprising a rotatable drum and oppositely arranged movable brake-shoe members adapted for frictional braking engagement with the drum, said brake-shoe members having arm portions at their upper ends extending inwardly to overlie the drum and each extending to the opposite side of the neutral axis, resilient pressure means operative to apply equal pressures upon each of the brake-shoes normally to force them inwardly into braking engagement with the drum, an electric magnet interposed between the arm portions of the shoes and having oppositely movable armatures connected to the respective arm portions and operative to separate the brake-shoes when energized, substantially as described.

3. A device of the character described comprising a rotatable drum and oppositely arranged movable brake-shoe members adapted for frictional braking engagement with the drum, said brake shoes having arm portions at their upper ends extending inwardly to overlie the drum and each extending to the opposite side of the neutral axis, resilient pressure means operative to apply each pressure upon each of the brake members normally to force them into braking engagement with the drum, means to adjust the pressure imparted by the pressure means, an electro-magnet interposed between the arm portions of the shoes and having oppositely movable armatures connected to the respective arm portions and operative to separate the brake-shoes when energized.

4. A device of the character described comprising a rotatable drum and oppositely arranged brake-shoes pivotally supported centrally below the drum and adapted for frictional engagement with the drum, said brake-shoes having arm portions at their upper ends extending inwardly over the drum to the opposite side of the neutral axis thereof, with their extremities in opposite relation, a pressure bolt arranged to extend outwardly through each of the brake-shoe members, adjustable bearing nuts threaded on the ends of said bolt, compression springs interposed between the nuts and the brake-shoes and operative to force the shoes into braking engagement with the drum and an electric solenoid magnet connected to the opposed extremities of the arms and operative to release the shoes from the braking engagement.

5. A device of the character described comprising a rotatable drum and oppositely arranged brake-shoes pivotally supported centrally below the drum and adapted for frictional engagement with the opposite pe-

ripheral surfaces of the drum, said brake-shoes having arm portions at their upper ends extending inwardly over the drum to the opposite side of the neutral axis thereof with their extremities in opposite relation, a pressure-bolt arranged to extend outwardly through each of the brake-members, adjustable bearing nuts threaded on the ends of said bolt, compression springs interposed between the nuts and the brake-shoes and operative to force the shoes into braking contact with the drum and a solenoid electric magnet connected to the opposed extremities of the arms and operative to release the shoes from braking engagement and said solenoid having oppositely movable armatures and connections from the armatures to the respective arms of the shoes, substantially as described.

6. A device of the character described comprising a rotatable drum suitably journaled and oppositely arranged arcuate brake-shoe members pivotally supported centrally with relation to the drum, said brake shoes having arm portions at their upper-ends extending inwardly over the drum and each having its end portion extended to the opposite side of the central vertical plane of the drum whereby the said end portions are in crossed relation, resilient pressure means operative to move the brake-shoe members into braking engagement and electro-magnetic means connected to the arm portions of the respective shoes and adapted to release the brake-shoes by inwardly moving the arm portions, substantially as described.

7. A device of the character described comprising a rotatable drum suitably journalled and oppositely arranged arcuate brake-shoe members pivotally supported centrally beneath the drum, said brake-shoes having arm portions at their upper ends extending inwardly over the drum and each having its end portion extended to the opposite side of the central vertical plane of the drum whereby the said end portions are in crossed relation, resilient pressure means operative to move the brake-shoe members into braking engagement and electro-magnetic means connected to the arm portions of the respective shoes and adapted to release the brake-shoes by inwardly moving the arm portions and means to limit the movement of the brake-shoe members, substantially as described.

Signed at New York city in the county of New York and State of New York this 3d day of June A. D., 1918.
